Specification for Design.

Patented Oct. 5, 1920.

Application filed November 12, 1918. Serial No. 262,257. Term of patent 3½ years.

To all whom it may concern:

Be it known that I, WILLIAM F. BOHANNON, a citizen of the United States, residing at Houston, in the county of Harris and State of Texas, have invented a new, original, and ornamental Design for a Toy, of which the following is a specification, reference being had to the accompanying drawing, forming part hereof.

The figure is a perspective view of a toy, showing my new design.

I claim:

The ornamental design for a toy as shown.
WILLIAM F. BOHANNON.
